REDUCTION OF NOISE

Rogers M. Smith, Merchantville, N. J., assignor
to Radio Corporation of America, a corpora-
tion of Delaware

Application September 30, 1936, Serial No. 103,398

6 Claims. (Cl. 250—20)

This invention relates to the reduction of the noise produced in radio receivers and similar apparatus by impulses extraneous to the desired signal impulses, and has for its principal object the provision of an improved apparatus and method of operation whereby such noise is substantially eliminated or greatly minimized.

In the development of radio receivers and the like, many sources of electrical impulses have come to be recognized as productive of undesired noise. Among these may be mentioned static, electric street car lines, internal combustion engines, electric elevators and other devices which involve the control and utilization of electricity. The elimination of the undesired effects of these extraneous impulses is a problem susceptible of a number of different solutions many of which involve the use of complicated and expensive apparatus or are not altogether effective.

In its broader aspects, the solution herein disclosed involves the provision of (1) means for maintaining a substantially constant signal level, (2) means for limiting the output capabilities of the apparatus, and (3) means for adjusting the output limiting means to permit operation at different signal levels. Stated more specifically, the apparatus of the present invention may include a reflex circuit in which an audio frequency amplifier is associated with means for automatically controlling its volume, a control member adapted simultaneously to adjust the signal input of this audio frequency amplifier and the screen grid potential of the output stage of the amplifier and a tone compensation circuit associated with one or more stages of the amplifiers. As will hereinafter appear, certain rearrangements of these various elements may be made without defeating the objects of the invention.

Among the further objects of the invention are (1) the provision of an improved automatic volume control system which operates with a substantially flat characteristic, (2) the provision of an improved control means for correlating the signal level and output capabilities of a signal amplifying channel and (3) the provision of an improved reflex circuit which is not subject to some of the difficulties heretofore encountered in the use of such circuits.

The invention will be better understood from the following description when considered in connection with the accompanying drawings and its scope is set forth in the appended claims.

Referring to the drawings

Fig. 1 is a wiring diagram of a radio receiver provided with a reflex circuit which includes an automatic volume controlled audio frequency amplifier having its signal input level controlled in accordance with the screen grid potential of the amplifier output stage, and

Fig. 2 is a similar diagram of a modified radio

receiver wherein the volume levels at the reflex circuit and at a following audio frequency stage are simultaneously adjusted. It will also be noted that somewhat different tone compensation systems are utilized in the apparatus of Figs. 1 and 2.

The circuit of Fig. 1 includes a signal pick-up device such as an antenna 10 from which signal impulses are supplied to a utilization device such as a loudspeaker 11. Between the antenna 10 and loudspeaker 11 is interposed a signal amplifying channel which includes (1) radio frequency stages 12 and 13, (2) an electron discharge device 14 (RCA Radiotron 6B7) which functions as an intermediate frequency amplifier and as a detector and audio amplifier, (3) an audio frequency amplifier 15 (RCA Radiotron 6L7) interposed between the detector and audio frequency stages of the device 14 and (4) an audio frequency amplifier 16 (RCA Radiotron 41).

In the operation of the apparatus of Fig. 1, intermediate frequency signal impulses applied to the control grid 17 of the device 14 are amplified by this device and applied through an intermediate frequency transformer 18 to the detector electrodes 19—20. The detector output circuit includes series resistor sections 21 and 22, and a cathode resistor 23 which are shunted by capacitors 24, 25 and 26 respectively. From the upper terminal of resistor section 21, an automatic volume control bias potential is applied through a resistor 27 to the control grids of the radio frequency stages 12 and 13. A similar bias potential is applied from the upper terminal of the resistor section 22 through a resistor 28 to an intermediate grid 29 of the audio amplifier 15. Signal input impulses are applied from the adjustable terminal 30 of the resistor section 22 through a capacitor 31 to the input circuit of the audio frequency amplifier 15 from the output circuit of which the amplified signal impulses are applied through a capacitor 32 to the control grid 17 of the device 14. These impulses are amplified by the device 14, are applied through a coupling assembly including resistors 33 and 34 and a capacitor 35 to the input circuit of the audio frequency amplifier 16 by which they are further amplified and applied through a coupling transformer 36 to the loudspeaker 11.

It will be noted (1) that a capacitor 37 is provided to exclude intermediate frequency impulses from the input circuit of the device 16, (2) that a tone compensation circuit which includes the series resistor 38 and capacitor 39 and the shunt resistor 40 and capacitor 41 is connected between the audio frequency output and input circuits of the device 14 and (3) that the adjustable terminal 30 of the resistor section 22 and the adjustable terminal 42 of a resistor 43 connected in the screen grid circuit of the device 16 are ar-

ranged to be simultaneously adjusted by a common control member 44.

In practicing the invention, the adjustments of the terminals 30 and 42 are so related that the device 16 operates just below saturation and the knee of its characteristic curve, and thus by saturation the relatively high amplitude noise impulses are limited to the signal level. It has been found that the apparatus operates at substantially constant signal level. Under these conditions, noise impulses of an amplitude exceeding that of the signal are effectively limited by the device 16 and this condition of operation is readily attained at different operating levels through the simultaneous adjustment of the terminals 30 and 42.

Considered apart from the elimination of noise, the above described reflex circuit has the important advantage that it effects a great improvement in automatic volume control. Thus it has been found that with an input variation of 10,000 to 1 the inclusion of the automatic volume controlled amplifier 15 in the reflex circuit results in a reduction of the output variation from 50 to 1 to 2 to 1, thus effecting a vast improvement in signal level stability.

The apparatus of Fig. 2 is similar in many respects to that of Fig. 1 and will be readily understood without detailed explanation. It differs in that (1) the audio frequency amplifier 15 is not included in the reflex circuit and the control grid of amplifier 16 is so biased as to obstruct the passage of relatively high amplitude noise impulses and (2) the tone compensation circuit is connected across the audio frequency amplifier 16.

It will be observed that automatic volume control is applied to the amplifiers 12 and 13 from the upper terminal of the resistor section 21 through a battery 45 and the resistor 27; that a 40 audio frequency signal input is supplied from the adjustable terminal to the input circuit of the device 14; and that the member 40 is utilized simultaneously to control the adjustment of the volume or level control terminal 30 and of the terminal 46 of the input resistor 47 of the device 15. The operation of this apparatus is similar to that of Fig. 1 and will be readily understood in view of the foregoing explanation.

I claim as my invention:

50 1. A signal channel including serially connected amplifier tubes, means for controlling the gain of the first of said amplifier tubes, means for adjusting a bias potential of the second of said amplifier tubes to control the saturation thereof, means for simultaneously operating said controlling and adjusting means to maintain said bias potential at a value such that relatively large amplitude noise impulses are limited by saturation of the second tube to the level of the signal impulses, and additional means for regulating the gain of the first of said amplifier tubes in accordance with variations in signal strength.

65 2. A signal channel including serially connected amplifier tubes, means for controlling the gain of the first of said amplifier tubes, means including a screen grid electrode for adjusting a bias potential of the second of said amplifier tubes to control the saturation thereof, means for simultaneously operating said controlling and adjusting means to maintain said bias potential at a value such that relatively large amplitude noise impulses are limited by saturation of the second tube to the level of the signal impulses, and additional means for regulating the gain of said

amplifier tubes in accordance with variations in signal strength.

3. A signal channel including serially connected amplifier tubes, means for controlling the gain of the first of said amplifier tubes, means for adjusting a bias potential of the second of said amplifier tubes to control the saturation thereof, means for simultaneously operating said controlling and adjusting means to maintain said bias potential at a value such that relatively large amplitude noise impulses are limited by saturation of the second tube to the level of the signal impulses, additional means for regulating the gain of the first of said amplifier tubes in accordance with variations in signal strength, and tone compensation means connected across one of said amplifier tubes.

4. The combination of an electron discharge device provided with an input circuit including a cathode and control grid, with an output including said cathode and an anode and with a detector circuit including said cathode and an auxiliary anode, means including a radio frequency amplifier for energizing said input circuit, coupling means interposed between said output and detector circuits, means including an audio frequency amplifier interposed between said detector and input circuits, and means associated with said detector circuit for automatically regulating the gain of said radio and audio frequency amplifiers.

5. In a signal amplifying channel, the combination of an amplifier tube having a cathode, a control grid, an output anode, a screen grid between said control grid and output anode, and a diode rectifier anode associated with the cathode, means for applying modulated high frequency signals to the control grid, means for coupling the output anode with said diode anode, an output resistor in circuit with said diode anode and cathode, an electric discharge amplifier device having a cathode, a control grid connected with said output resistor to receive rectified signals therefrom, a second control grid connected with said output resistor to receive a biasing potential therefrom responsive to signal strength variations, and an output anode coupled to the control grid of the first named amplifier tube to apply amplified and rectified signals thereto, means for deriving said rectified and amplified signals from the output anode of said first named amplifier tube including an audio frequency amplifier tube having a screen grid, and means for simultaneously adjusting the potential of said screen grid and the signal potential applied to the control grid of said second named electric discharge device.

6. In a signal amplifying system, the combination of an electric discharge amplifier device including a diode rectifier, means for applying signals to said amplifier device, means for applying amplified signals from said device to said rectifier, an audio frequency amplifier coupled to said first named amplifier device to receive rectified and amplified audio frequency signals therefrom, means for controlling the gain of said amplifier devices in accordance with the variations in the value of the signal voltage derived from said rectifier, and means for manually adjusting the gain controlling potential applied to said first named amplifier device and the signal potential applied to said second named amplifier device in predetermined relation to each other.

ROGERS M. SMITH.
